UNITED STATES PATENT OFFICE.

FRANK M. ASHLEY, OF BROOKLYN, NEW YORK.

PEN.

1,248,989.

Specification of Letters Patent. Patented Dec. 4, 1917.

Application filed July 6, 1914. Serial No. 849,027.

To all whom it may concern:

Be it known that I, FRANK M. ASHLEY, a citizen of the United States and a resident of New York city, borough of Brooklyn, in the county of Kings and State of New York, have invented certain new and useful Improvements in Pens, of which the following is a specification.

This invention relates to pens, particularly to a type of pen in connection with which water is utilized during writing to dissolve a stick of solid ink.

The principal objects of the invention are to provide a pen of this character which is simple, inexpensive and efficient and reliable in operation.

The various further objects and advantages will more fully appear hereinafter.

In the drawing illustrating this invention,

Figure 1 is a view illustrating my invention as applied to a dip pen.

Fig. 2 illustrates a modified form in which the holder for the ink may be of metal.

Fig. 3 is a bottom plan of a further modified form illustrating the ink retainer held by the overturned tongues on the pen point.

Fig. 4 is a detail plan view of the ink retainer detached.

Fig. 5 is a side view of the pen point and ink holder shown in Fig. 4.

Fig. 6 is a still further modification in which the ink retaining portion is shown as integral with the pen holder and the pen retained by a metal ferrule.

Referring in details to the drawings, particularly to Fig. 1, the nib 20 has associated therewith a plug 21 together fitting into a holder 22. The plug is formed with a recess 23 under the nib in which is snugly disposed a solid stick of ink above the eye of the nib. Lateral apertures 25 are formed in the plug at the forward end thereof, these apertures communicating with the recess 23 and thus forming a sort of reservoir for the water which may collect in the recess 23. Thus, the pen, to a certain extent, acts as a fountain pen in that after being once dipped in the water, sufficient liquid is taken up to write for a considerable period. The stick 24 as above stated fits snugly in the recess against the bottom of the nib, thus exposing only the end thereof to the liquid, prolonging the effective life of the stick.

Referring to the modified form illustrated in Fig. 2, the pen is provided with a nib

30 and a metal ink retainer 31 formed with a tongue 32 passing into the holder 33. The tail of the pen and the tongue 32 of the ink retainer are disposed at opposite sides of the compressible core member 34 in the pen. The ink retaining member 31 is provided with a recess 35 and apertures 36 at the forward end thereof corresponding to the form illustrated in Fig. 1.

In the modification illustrated in Figs. 3 and 5, the nib 40 may be of a type having inwardly turned tongues 41 adjacent to the mid-length thereof in which tongues is held the ink retainer 42. The latter may consist of a plug of wood or metal having a recess 43, in which is retained the stick of solid ink 44. Apertures 45, are formed in the forward end of the recess and transversely thereof to permit the water to fill the recess as in the other forms above described. This forms a very cheap construction which may be attached to standard nibs and held therein by one of the standard parts thereof.

In the modification illustrated in Fig. 6, the holder 50 is formed with a reduced portion 51 which terminates in the flattened ink retaining portion 52 having a recess 53 in the upper side thereof in which is retained the stick of solid ink 54. The transverse apertures 55 are formed at the forward end of the recess as in the other forms described. The nib 56 is held in place above the recess by means of a ferrule 57 of metal or some other suitable material.

It will be seen that I have provided a pen of inexpensive construction which may be used for dipping into water to write with ink. The solid stick of ink is securely held and a reservoir is formed under the nib which holds a sufficient supply of liquid to permit the use of the pen for a comparatively long interval without dipping into the liquid again. By exposing only the end of the stick to the action of the liquid, the life of the stick is increased and the quality of the ink is rendered uniform. Also when the fluid portion of the supply in the recess or reservoir is exhausted, a heavier residue remains which is too thick to feed down the nib easily, but on the other hand, serves to immediately convert the next charge into writing fluid when the pen is dipped into the water to renew the supply in the recess or reservoir. No matter how much the ink stick may be reduced in size, it is still se-

curely held in the recess and will not be lost or soil the fingers of the user.

Having thus described my invention, I claim as new and desire to secure by Letters

5 Patent:

1. A pen comprising a feed or plug portion having a slot in its surface at its forward end of sufficient width and length to hold a cylindrical portion of ink stick, and 10 having a portion of ink stick located in said slot; a pen, the shank of which overlies and holds said ink stick in said slot at a distance from its front end whereby a chamber is formed between the front end of the slot 15 and the front end of the ink stick.

2. A pen comprising a feed or plug portion having a slot in its surface at its forward end of sufficient width and length to hold a portion of ink stick and having a portion of 20 ink stick located in said slot; a pen having an eye, the shank of said pen closing said slot and holding said ink stick therein so that its front end is located behind the eye

of the pen whereby a chamber is formed 25 between the end of the ink stick and end of the slot which is open to the atmosphere through the eye of the pen.

3. A pen comprising a feed or plug portion having a slot in its surface of sufficient width and length to hold a portion of ink 30 stick, and having an opening or notch intersecting said slot at its front end, and a pen the shank of which overlies and closes said slot and is adapted to hold a portion of ink stick in said slot so as to expose its front 35 end to said opening or notch and thus provide a chamber between the end of the ink stick and slot.

Signed at New York city, in the county 40 of New York, and State of New York, this 1st day of July, A. D. 1914.

FRANK M. ASHLEY.
